W. H. Wattles Case. Atty:

UNITED STATES PATENT OFFICE

ALFRED E. HUDD, OF LONG PARK, CHESHAM BOIS, ENGLAND, ASSIGNOR, BY MESNE ASSIGNMENTS, TO ASSOCIATED ELECTRIC LABORATORIES, INC., OF CHICAGO, ILLINOIS, A CORPORATION OF DELAWARE

TRAIN STOP SYSTEM

Application filed May 31, 1928, Serial No. 281,616. Renewed March 23, 1932.

The present invention relates in general to train control systems, but is particularly concerned with the development of an automatic train stop system of the intermittent inductive type, and may be considered as a further development of the type of system disclosed in the co-pending Hudd application, Serial No. 213,455, filed August 17, 1927.

One of the principal objects of the present invention is to further simplify and improve the design of the equipment, making it more reliable and more economical to build and maintain.

Another object is to arrange the apparatus in such a manner that no single unit of the same is of such bulk as to render installation, especially in the cab of the vehicle, difficult. This is accomplished in the present case by substituting a number of small units for a large casting, formerly serving as a structure for these units.

A further feature covers an arrangement for suspending the vehicle relay or receiver in a simple manner and providing in conjunction therewith means for detecting any movement of the receiver with respect to the vehicle should an obstruction be encountered by the receiver to move it out of active relation with the trackway elements.

Other objects of the invention not particularly pointed out will become obvious as the specific description of the invention proceeds.

The invention is disclosed in two sheets of drawings. Fig. 1 diagrammatically discloses the mechanism and circuits of the locomotive equipment and one set of associated trackway elements, while Figs. 2 and 2A are views, in elevation, of the carrier and housing for the locomotive receiver relay assembly.

The vehicle equipment, as shown in Fig. 1, consists of an applicator having an arm 30', through the medium of which the engineer may at any time manually apply the brakes of the vehicle in the usual and well known manner. This applicator is equipped with a pneumatically operable piston 6 for bringing about an automatic brake application under certain conditions. An electropneumatic valve 2, normally held closed by its energized winding, is effective, upon deenergization, to

release the air pressure stored up in two reservoirs B and C through the whistle 5, to warn the engineman of the fact that a signal has been passed and to ultimately bring about a brake application unless the electropneumatic valve 2 is again energized within a predetermined interval as will subsequently be described. A light control relay 50 is provided for and functions in conjunction with the armatures and contacts of a receiver relay R and with the contacts of a pneumatic contactor PC to maintain the appropriate lamp G or P lighted in accordance with traffic conditions.

The receiver R is a polarized relay along the general lines of the one disclosed in the co-pending application previously referred to, but is slightly different in that it has two independently controlled armatures. The trackway devices, diagrammatically shown, comprise a permanent magnet 41 and an electro-magnet, 42, placed approximately six feet from each other at the exit end of a block. A semaphore signal is also shown indicating clear conditions, and for simplicity's sake, indicating that it directly completes the circuit for the electromagnet trackway element 42 when in this position only. In actual practice, however, the use of a circuit control system of the type shown in Fig. 3 of the co-pending application Serial No. 213,455, is contemplated.

The pneumatic contactor consists of a casting 34 on which is mounted a disk 13 of leather, rubber, or other suitable material provided with a contact operating button 44. Also suitably mounted upon this casting is a contact arm 14 and associated lower and upper contact elements. A cover 35 completely encloses and protects the contact mechanism. The lower part of the casting 34 has a number of perforations 43 surrounding the perforations to which the connecting pipes 33 and 28 are connected. The contact mechanism and various apertures are so designed that a pressure pulse of 40 lbs. or over through the pipe 33 or a continued flow of air at 40 lbs. pressure through the pipe 28 will be required to actuate the arm 14.

The stop detector unit SD is of the type

shown and described in a co-pending Hudd application, Serial No. 274,412, and filed May 2, 1928. This stop detector, as described in the co-pending application referred to, functions in response to the application of air to pipe 45 to apply air to the pneumatic contactor PC, via pipe 28, only in case the locomotive wheel 31, associated with element 21, is stationary at the time pressure is applied 10 to the stop detector, all as clearly described in the co-pending application referred to.

The various devices on the vehicle as shown in Fig. 1 are in their normal operating positions, that is, the positions assumed when 15 the equipped vehicle is traveling under clear traffic conditions with all circuits and devices properly energized. For convenience, the well known positive and negative symbols have been used to designate the opposite poles 20 of a source of energy, preferably a storage battery, generator, or a suitable combination of the two.

In order to explain the invention it will first be assumed that a vehicle is equipped 25 with the apparatus and circuits of Fig. 1 and is operating under clear traffic conditions, as indicated by the semaphore S.

The armatures 58 and 59 of the receiver relay R are normally polarized by the permanent magnet P. It will therefore be obvious 30 that the normal magnetic circuits are such that the armatures are magnetically biased by the presence of the permanent magnet P to either of their pole pieces to which 35 they have been attracted.

Operation

When a train approaches the exist of a block the pole pieces 43' and 44' first pass 40 over and within inductive relation to the trackway magnet 41 and then the pole pieces 41' and 42' pass over this magnet. The polarity of magnet 41 is such that it weakens the attractive effect between armature 58 45 and the pole piece 44' produced by magnet P and strengthens the attractive effect between this armature and of the pole piece 43', which causes armature 58 to be rotated in a clockwise direction, thereby opening its 50 lower and closing its upper contacts. As the vehicle proceeds pole pieces 41' and 42' come under the influence of the magnet 41 and armature 59 is also caused to rotate in a clockwise direction, to open its upper and close 55 its lower contacts.

The armature 58, at its lower contact, breaks a normally established circuit for the electropneumatic valve 2 which releases and permits air to exhaust through the whistle 5. 55 This circuit formerly extended from the negative terminal, through the armature 58 and its lower contact, conductor 51, the winding of the electropneumatic valve 2, conductor 52, triangular plate 47, to be later described, upper contact and armature 59 and

thence to the positive terminal. The armature 59, in operating, at its upper contact opens a second point in the traced circuit for the electropneumatic valve 2, and in addition, at its lower contact completes an operating circuit for the light control relay 50 via conductor 3. However, the closure of this circuit is without effect at this time as the light relay is already held up over a stick circuit including its contacts 8 and the lower contact and lever 14 of the pneumatic contactor PC.

A circuit for the green lamp G normally maintained in multiple with the electropneumatic valve 2, also includes conductors 53 and 54, and contacts 10 of the light control relay 50. Since the lamp G is in multiple with the electropneumatic valve 2, the instant that the elements 43' and 44' of the receiver relay R pass over a permanent magnet, such as 41, not only is the electropneumatic valve deenergized, but in addition the green light G is extinguished.

As soon as the train travels approximately six feet, after the receiver has encountered the trackway magnet 41, the receiver passes over the electromagnet trackway element 42, which, under the condition assumed, is energized. The electromagnet 42 is of a polarity opposite to that of the permanent magnet and therefore functions to restore the armatures 58 and 59 to their initial positions, in which they are shown. This causes the formerly traced multiple circuit for the electropneumatic valve 2 and green lamp G to be again completed. The effect of passing over these magnets therefore, under the circumstances assumed, is to cause the warning whistle of the electropneumatic valve to be actuated momentarily and give a toot, so to speak, and in the green lamp being extinguished momentarily. The operation of these signals in this manner serves to notify the engineer both audibly and visibly, that the vehicle has passed a "proceed" signal and has therefore entered a block in which traffic conditions are favorable.

I will now assume that the train has arrived near the exit of a block at which the signal S is in its "caution" or "stop" position. With this state of affairs existing, when the receiver R passes over the permanent magnet 41 the foregoing described circuit changes take place as before. However, since the electromagnet 42 is deenergized at this time, the circuit conditions brought about by magnet 41 will remain unchanged. Consequently the electropneumatic valve 2 will remain deenergized and the warning whistle 5 will continue to sound. Also, the green light G will remain extinguished.

Main reservoir pressure is normally maintained in the reservoirs B and C through restricted orifices 12 and 13, respectively, and the size of the B reservoir, restricted orifice

12 and the orifice through the warning whistle 5 is each so proportioned that six seconds must expire before the pressure in reservoir B can be lowered to a point where it is insufficient to hold the valve element 1 of the applicator closed. Therefore, if the electro-pneumatic valve 2 is again energized during this interval an automatic brake application is prevented. The engineer is provided with an acknowledging valve 61, which, if operated during this interval, permits a pulse of air from the reservoir C to be applied to the diaphragm 13 of the pneumatic contactor, which will respond and operate the lever 14 into engagement with its upper contact. Owing to the limited capacity of the reservoir C and due to the restricted orifice 13, lever 14 can however be only actuated momentarily by an actuation of the valve 61. Lever 14 in operating completes a circuit from the positive terminal, through the lever 14 and its upper contact, conductor 55, and to and through the windings 17 and 18 of the receiver R to the negative terminal. These windings, when energized are effective to swing the armatures 58 and 59 back to their initial positions. A further result which occurs responsive to the momentary raising of lever 14 of pneumatic contactor is the breaking, at the lower contact of lever 14, of the holding circuit of the light control relay 50, which therefore drops its armature as soon as the armature 59 is restored. Relay 50 at its contacts 11 now completes a circuit for the purple lamp P in multiple with the electro-pneumatic valve 2 instead of for the lamp G. The lighted condition of the purple lamp serves to warn the engineer that he is about to pass through a block under restricted traffic conditions.

60 If for any reason whatever the engineer fails to operate the acknowledging valve 61 during the six second period the pressure drop in reservoir C will be such that an operation of the acknowledging lever 61 will be without effect to cause the movement of the lever 14. Also, the pressure in reservoir B will be insufficient to maintain the valve element 1 in closed position. This valve element will therefore move to the right and permit main reservoir pressure to be supplied to the piston 6, causing a service application of the brakes to be made.

65 The engineer cannot remove the brake application until the vehicle has actually been brought to a stop, for, as previously explained, the actuation of the acknowledging valve 61 will be without effect owing to the drop in pressure in reservoir C caused by the exhaust through whistle 5 for more than the six second interval.

70 When the vehicle has been brought to a stop the engineer may cut off the application of air being supplied to the actuator piston 6 by actuating the stop detector valve 16. The actuation of this valve permits main reservoir

75 pressure to be applied to the stop detector SD which functions to open up a passage permitting main reservoir pressure to be applied to the pneumatic contactor via pipe 28 if, and only if the vehicle is at a standstill, as clearly brought out in the co-pending application Serial No. 274,412, formerly referred to. The lever 14, upon operating, at its lower contact breaks the stick circuit of relay 50 and at its upper contact completes the previously traced circuit for causing the armatures 58 and 59 to be restored to again complete the circuit for the electro-pneumatic valve 2. The armature 59, upon being restored also, at its lower contact now breaks the energizing circuit of the light control relay, which drops its armature before lever 14 can again close the stick circuit. The relay 50 therefore at its contacts 11 now completes a circuit for the purple lamp P. It will be seen therefore that although the train can proceed as soon as the pressure in reservoir B becomes high enough to restore the valve 1, as occurs shortly following the reenergization of the electro-pneumatic valve 2, the purple lamp will remain lighted 80 to continually warn the engineer that he is in caution territory.

85 I will now assume that the vehicle is again about to enter a block in which favorable traffic conditions exist. Under these conditions, when the receiver passes over the permanent magnet 41 the armatures 58 and 59 are moved to their alternate positions as before with the same results, and the light control relay is again energized by the circuit completed for it through armature 59. The purple lamp is therefore extinguished, but the circuit of the green light is not yet completed owing to the alternate position of armature 58. An instant later, however, when the receiver passes over the energized electromagnet 42, armatures 58 and 59 are again restored to their initial position, again completing the circuit of the electro-pneumatic valve 2 and of the green lamp G. The light control relay does not become deenergized now even though its energizing circuit is again broken at the lower contact of armature 59 because a stick circuit was completed upon its energization through its contacts 8 and through the lower contact and lever 14 of the pneumatic contactor. The vehicle equipment is therefore in the same condition as it originally was when the description of the operation was begun, under the assumption that the vehicle was traveling in clear territory.

90 On certain installations it may be desirable to provide means for checking up the number of times the receiver relay is operated. This is accomplished in the present case by connecting a meter 37 to the upper contact of armature 58 of the receiver relay. The time at which acknowledgement is made is also recorded by the recorder 31', which is

connected directly to the conductor 55 leading to the upper contact of the pneumatic contactor.

Referring to Figs. 2 and 2A, the type of receiver carrier employed in the present system will be explained. A pair of brackets 60 are securely fastened to the frame of the tender and to these are secured two triangular plates 47 and 48, which are held in place by a bolt 49. To the plates 47 and 48 are secured, by machine screws 62, the housing 57 having a cover 56 which encloses the relay or receiver relay apparatus R, diagrammatically shown in Fig. 1. The particular feature of this method of carrying the receiver relay has to do with a protective arrangement for guarding against the receiver unit being pushed out of inductive relation by a track obstruction without the knowledge of the engineer. This is accomplished by making perforations in the plate 47 and the associated bracket 60 which are in alignment when the receiver unit is in the proper relation to the trackway. These perforations are provided with hard rubber bushings 59 and the conductor 51 leading to the electropneumatic valve 2 passes through these perforations. With this arrangement, should the receiver unit be rotated on the bolt 49, conductor 51 will be sheared in two causing the electropneumatic valve 2 to become deenergized and bring about a brake application. It will be understood that although only one conductor is shown as passing through the perforation in the plate 47 and bracket 60 several of the conductors may be brought through same, to obtain further protection, or a similar arrangement may be provided between the plate 48 and its associated bracket.

What I claim is:

1. In a cab signal system, a pair of lamp signals, a normally energized relay having a pair of normally closed contacts included in a circuit including one of said signals and having another pair of normally open contacts included in a circuit including the second signal of the pair, a second relay having a pair of normally closed contacts included in a circuit common to both of said lamp signals, means for actuating said second relay, thereby breaking the common circuit for said signals and other means for then actuating the first and restoring the second relay to complete the circuit of the second lamp signal of said pair.

2. In a cab signal system, a normally energized light control relay, a signal having a circuit including normally closed contacts of said relay, a second signal having a circuit including normally open contacts of said relay, other means on the vehicle under control of trackway means to cause the said light control relay to become deenergized and open the circuit of the first signal and close

a point in the circuit of the second signal and manually operable means for causing the actuation of said other means to complete the circuit of said second signal.

3. In a cab signal system, a cab carried relay, a cab signal and a circuit therefor completed while the vehicle is traveling under clear traffic conditions, means for inductively actuating said relay to extinguish said signal, means for again inductively actuating said relay to again light said signal, other means for actuating said relay, and a second relay controlled by said other means to prevent the signal being lighted in the latter instance. 70

4. In a train control system, trackway equipment comprising a permanent and an electromagnet at the exit end of each block section, a cab equipped with a receiver relay having two armatures separably operable by magnetic influences transmitted to the receiver by each of said magnets, and train control equipment controlled by said armatures. 80

5. In a train stop system, a receiver relay, means for suspending said receiver relay under a vehicle in operative relation with trackway elements and a train control circuit passing through perforations in said means, the material surrounding said perforations functioning as shears for severing said circuit should the receiver be moved out of operating relation with said trackway elements. 90

6. In a train stop system, an impulse receiver suspended from a vehicle, electrical conductors extending between said vehicle and receiver, and means for shearing one of said conductors consequent to movement of said receiver relative to the vehicle. 100

7. In a train control system, a normally energized relay and magnet respectively, lamp signals under control of said relay, means for causing a change in the condition of one of said lamp signals and to visually and audibly warn an engineman of a changed traffic condition, means controlled by an engineman for causing the reenergization of said magnet, and auxiliary means also effective, incidental to the actuation necessary to reenergize said magnet, to interrupt the circuit 110 of said relay to further modify the condition of one of said lamp signals. 115

8. In a cab signal system, a pair of lamp signals, a vehicle carried pickup relay and a light control relay, respectively, circuits for said lamp signals including contacts of said relays, trackway means for causing the pickup relay to operate and interrupt the circuit of one of said signals, and manually controlled means for causing the circuit of said light control relay to be interrupted and the pickup relay to be again operated to complete the circuit of said other lamp signal. 120

9. In an automatic train stop system, an electro-pneumatic valve and a signal control 130

relay, multiple circuits for normally maintaining said valve and relay energized, a pair of cab signals, circuits for said signals each including contacts of said relay, traffic controlled means for interrupting the circuits of one of said signals and of said valve, and manually controlled means operable to interrupt said relay circuit to cause said relay to close the circuit including the other of said signals and to at the same time cause the re-establishment of the valve circuit.

10. In a cab signalling system, a pair of signals, a relay, a holding circuit over which said relay is normally maintained energized, contacts on said relay in a normally closed circuit including one of said signals, other contacts on said relay in a normally open circuit including the other of said signals, a second relay having a pair of normally closed contacts included in a circuit common to said signals, means for actuating said second relay to break the common circuit and thereby retire either signal which may at the time be active, and manually controlled means for interrupting the holding circuit of said first relay to cause it to close a point in the normally open signal circuit and for establishing a restoring circuit for said second relay to thereby cause it to operate and complete the circuit of the other of said signals.

11. In a train control system, a receiver relay operable independently of and also in accordance with traffic conditions; vehicle signals for displaying non-restrictive and restrictive indications, respectively; a normally energized control relay for assisting said receiver relay in the control of said vehicle signals, an energizing circuit for said signal control relay controlled exclusively by said receiver relay, a manually controlled means for varying the signal control effect caused by an actuation of said receiver relay, and a holding circuit for said signal control relay controlled exclusively by said manually controlled means.

12. In a train control system; a vehicle equipped with signals for displaying non-restrictive and restrictive indications displayed by signals associated with the track-way, vehicle carried means operated when the vehicle encounters a wayside signal for retiring the active one of said vehicle signals irrespective of which signal is active, means for then automatically rendering one of said vehicle signals active if the encountered wayside signal is displaying a non-restrictive indication, a normally energized relay for preventing the other vehicle signal from becoming active at such time, manually controlled means effective, when operated, to deenergize said relay to render the other vehicle signal active if the encountered signal is displaying a restrictive indication, and means for causing an automatic brake application to occur if the prompt operation of

said manually controlled means is neglected under the latter circumstances.

13. In a cab signalling system, the combination with a vehicle and trackway, of non-restrictive and restrictive signals in the vehicle, a double armature pickup relay suspended from the vehicle, permanent and electromagnet track elements for operating the armatures of said relay, a manually controlled normally open operating circuit for also operating the armatures of said pickup relay, another relay on the vehicle, and circuit connections within the vehicle controlled jointly by said relays and by said manually controlled circuit for substantially constantly maintaining the appropriate signal active.

In witness whereof, I hereunto subscribe my name this 25th day of May, A. D. 1928.

ALFRED E. HUDD.
